TOY TRUCK

Ira B. Gilford, Thousand Oaks, and Alan W. B. Nash,
Torrance, Calif., assignors to Mattel, Inc., Hawthorne,
Calif.

Filed Mar. 2, 1970, Ser. No. 21,671

Int. Cl. D21—01

U.S. Cl. D34—15

FIG. 7

FIG. 8

FIG. 1

FIG. 2

FIG. 3

FIG. 4

FIG. 5

FIG. 6

FIG. 1 is a rear perspective view of a toy truck showing our new design; and

FIG. 2 is a rear perspective view of the truck of FIG. 1 having a dump body in place of the concrete mixer body thereof; and

FIG. 3 is a front perspective view of the toy truck of FIGS. 1 and 2 with the rear body portions removed; and

FIG. 4 is a left side elevational view of FIG. 3; and

FIG. 5 is a top plan view of FIG. 4; and

FIG. 6 is a bottom plan view; and

FIG. 7 is a front elevational view of FIG. 3; and

FIG. 8 is a rear elevational view of FIG. 3.

We claim:

The ornamental design for a toy truck, as shown and described.
